AMBULANT TOY WITH ERRATIC STEERING MEANS

Oscar J. Pérez, Tampa, Fla.

Application February 2, 1948, Serial No. 5,877

1 Claim. (Cl. 46—212)

1
This invention relates generally to toys and more particularly to an ambulant toy comprising a chassis having steering and driving wheels, a motor and power transmission means to drive the driving wheel alternately forwardly and rearwardly and steering means which is also operated by the said motor.

A primary object of this invention is to provide a toy which will move along an irregular line or path which is apparently haphazard to the casual observer but which may be determined by the operator of the device.

Another object of this invention is to provide an ambulant toy in which the steering mechanism and the forward and rearward-drive mechanism operate independently of each other, and in which a set of replaceable cams are provided so that different paths will be followed by the toy when different cams are mounted therein.

Still another object, of specific character, is to provide improved steering and reversing means in a toy of this character.

And a last object to be mentioned specifically is to provide a device of this character in which all the elements thereof are relatively inexpensive and practicable to manufacture, the toy being safe as well as highly interesting to operate, readily susceptible of various types of ornamentation, and generally adapted for durable service.

With these objects definitely in view, this invention resides in certain novel features of construction, combination and arrangement of elements and portions as will be hereinafter described in the specification, particularly pointed out in the appended claim, and illustrated in the accompanying drawings which form a material part of this application, and in which:

Figure 1 is a view of this toy, largely in top plan, the outer decorative casing being removed and the motor assembly and housing therefor being shown in horizontal section as though taken on a plane immediately beneath the top plate of said housing;

Figure 2 is a vertical longitudinal sectional view of the assembled toy, the view being taken substantially on the line 2—2 of Figure 1, the casing for the toy being generally indicated in dash line;

Figure 3 is a three dimensional enlarged view of the sleeve mounted for rotation with the rear axle and carrying gear wheels, together with a lever used to shift the sleeve for selective forward and reverse driving of the toy;

Figure 4 is a three dimensional view of the drive shaft and associated parts;

Figure 5 is a lower plan view of the assembled

toy, the outside casing of the toy being removed as in Figure 1;

Figures 6, 7, and 8 are lower plan views of cams used in association with the steering mechanism of the toy and which are selectively mounted one at a time in the toy, that is, these cams are provided in a set of interchangeable units having different operative cam faces;

Figure 9 is a plan view of a simple cam used in connection with the shifting of the gears illustrated in Figure 3; and

Figure 10 is a transverse vertical sectional view, taken on the line 10—10 of Figure 1 and looking in the direction of the arrows.

Similar characters of reference designate similar or identical elements and portions throughout the specification and throughout the several views of the drawings.

Referring now to the drawings in detail, this invention comprehends provision of a chassis having a flat plate frame 10 with a front transverse member 12 bolted or riveted thereto as at 14, the base frame being reduced in width at the front end and generally rectangular, bearings 16 for the axle 18 of the rear wheels 20, and a housing 22 with an outturned attachment flange 24 bolted or riveted as at 26 to an intermediate portion of the plate frame 10.

The front wheels 28 are carried on stub axles 30 having steering arms 32 linked by a tie rod 34, and it will be noted that the transverse member 12 is offset downwardly as at 36 at each end of the reduced front portion of the plate frame 10.

A coiled spring motor assembly, generally indicated by the reference numeral 38 and referred to hereinafter simply as the motor, includes a coil spring 40, a shaft 42 driven directly thereby and carrying a gear 44 mounted thereon for rotation in one direction with the shaft 42 and driven by a pawl 46 and ratchet 48, but allowing the winding of the coiled spring 40 by means of a key, not shown, applied to the end 50 of the shaft, all in a well known manner which has become substantially conventional in toys of this character. The coil spring 40 is terminally secured as indicated at 52 to the housing 22 and the plate frame is apertured to receive a bearing 54 having an upstanding portion adapted to support the gear 44, a stepped portion fitted into the plate frame 10 and a depending portion 56, and in the embodiment illustrated in the drawing, this bearing 54 also partakes of the nature of a journal inasmuch as the bearing 54 rotates with the shaft 42, the depending portion 56 being

55 preferably hexagonal in cross section and adapted

to receive thereon the rotary cam 58, which will now be described. This cam is formed with a hexagonal recess and will be provided in a set in which the individual cams as illustrated in Figures 5, 6, 7 and 8 are similar except as to the configuration of the operational face thereof, that is, the configuration of the groove 62. Each of these individual cams is provided with a depending neck portion, the outer edge of which is indicated at 64 in Figures 5 to 8, and which is further illustrated at 66 in Figure 2. Each cam is also provided with a shoulder 68, and a second cam 70 fits on this neck portion 66 abutting the shoulder 68.

A steering lever 72 and a second lever 74 are pivotally mounted as indicated at 76 and 78 in spaced relation to and on the underside of the plate frame 10. The forward end of the steering lever 72 is pivoted as at 80 to the tie rod 34, the pivot connection including an elongated slotted plate 82 on the extreme forward end of the lever 72, while the rear end of the same lever has a cam follower operatively associated with the groove 62 in the cam 58.

The lever 74 does not have a cam follower of roller type and the extending portion 84 of the cam 70 forces this lever in one direction against the action of a biasing spring 86 connected to a rear portion of the lever 74 and to the plate frame 10 as indicated at 88, while the extreme rear end of this lever 74 is arranged in frictional engagement with and between the spaced parallel annular flanges 90 on a sleeve 92 as best illustrated in Figure 3. The central portion of the axle 18 is preferably square in cross section and the sleeve 92 is also a hollow square in cross section so that this sleeve is mounted for rotation with the axle and slidably longitudinally thereof. The sleeve 92 carries a pair of spaced beveled gears 94 selectively engageable with the drive gear 96. The drive gear 96 is carried on the lower end of the drive shaft 98 which is suitably journaled in the plate frame 10 and the top wall of the housing 22 and driven indirectly by the coil spring 40 through a set of reduction gears of any suitable character and indicated at 100, 102 and 104. While it is not thought necessary to elaborate on the reduction gear assembly, it should be noted that other reduction gears 106, 108, 110 and 112 and a suitable complement of shafting are used to connect a fly wheel 114 in this assembly to make the operation of the toy more uniform.

The second lever 74 is offset as at 116 so that the rear end portion 118 of the lever is substantially normal to the axle 18. The hexagonal aperture 120 in the second cam 70 is such as to allow this second cam to fit snugly over the neck portion 66 of the first cam 58 and both these cams are held in position by a transversely disposed strap member 122 having a hinge connection 124 with the plate frame 10 which will be

provided with a depending member to space the hinge 124 downwardly beneath the level of the plate frame 10 as indicated by the positioning of the hinge connection 124 in Figure 2, the drawings not showing this depending member except as indicated by the line 126 in Figure 5, while the other end of this member 122 is provided with any suitable latching means 128 whereby the member may be held secured to the plate frame 10 and securing the said cams in operative position.

The operation of this invention will be clearly understood from the foregoing description of the mechanical details thereof, taken in connection with the above recitation of the objects sought to be achieved by this invention. Minor variations from the embodiment disclosed may be made without departure from the spirit and scope of this invention, the limits of which scope should be determined according to the appended claim.

Having described the invention, what is claimed as new is:

An ambulant toy comprising a chassis having steering and driving wheels, cam means operatively secured on the chassis and a motor to drive the cam means, a lever having a cam follower operatively connected with said cam means and the steering wheels, and power transmission means connecting said motor with said driving wheels, said motor having a drive gear, said driving wheels having an axle rotatably mounted on the chassis and fixed against movement transversely of the chassis, a sleeve mounted for rotation with the axle and slidably longitudinally thereof, spaced gear wheels carried on said sleeve and selectively engageable with said drive gear, whereby said driving wheels may be rotated in two directions, and a second lever with a cam follower operatively connected with said cam means and with said sleeve, said cam means comprising separably interfitting sections each associated with one of said levers, said motor to drive the cam means including a vertical shaft extending to the underside of said chassis, said sections of the cam means being removably mounted on said shaft, and a strap member hinged to the underside of the chassis and releasably securable in position to hold said sections operably mounted on the shaft.
